Attorney

UNITED STATES PATENT OFFICE.

PIERRE JOSEPH HENRI BERNARD, OF MONTREAL, QUEBEC, CANADA.

RADIATOR.

1,371,725.

Specification of Letters Patent. Patented Mar. 15, 1921.

Application filed January 2, 1920. Serial No. 349,103.

To all whom it may concern:

Be it known that I, PIERRE J. H. BERNARD, a subject of the King of Great Britain, residing at Montreal, Province of Quebec, Canada, have invented certain new and useful Improvements in Radiators; and I do hereby declare that the following is a full, clear, and exact description of the invention, such as will enable others skilled in the art to which it appertains to make and use the same.

The present invention relates to improvements in radiators and appertains more particularly to water and air column type adapted for use in connection with steam or hot water heating systems.

The principal object of the invention is to provide a radiator of the water and air column type which can be manufactured in standard sections, so as to be easily mounted in any required length suitable for rooms of any size. Another object of the invention is to provide a radiator of this character in which, should a pipe or tube become worn or broken, another one may be easily and readily substituted therefor, and one which will be comparatively inexpensive in its cost of manufacture, thereby rendering the same commercially desirable.

Another object of the invention is to provide a radiator having the advantages of being demountable and at the same time having a greater heat radiating surface.

A still further object of the invention is to provide novel mounting means for the series of steam and heated air circulating tubes.

With the above and other objects in view which will hereinafter appear as the description continues, the invention consists of the novel features of construction, combination and formation of parts as will be hereinafter more fully described and particularly pointed out in the appended claims.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claims without departing from the spirit of the invention or sacrificing the efficiency of the same.

The invention has been illustrated in its

preferred embodiment in the accompanying drawings, wherein,

Figure 1 is a side elevational view of the improved radiator;

Fig. 2 is an end elevation of the same;

Fig. 3 is a fragmental plan elevation of the end casting of the radiator forming the subject matter of the present invention;

Fig. 4 is a partial vertical section on line 4-4 of Fig. 3;

Fig. 5 is a transverse vertical section on line 5-5 of Fig. 3; and

Fig. 6 is a transverse vertical section on line 6-6 of Fig. 3.

In carrying out the present invention, reference being had to the drawings in detail, there are provided a plurality of tubes 10, arranged transversely in series of four in this instance. Each of the tubes 10 comprising the series, is exteriorly screw threaded at the upper and lower ends and said threaded portions take into similarly threaded openings provided in the upper and base coupling members 11 and 12.

These coupling members 11 and 12 are of integral construction and formed with interior chambers 13 into which open the tubes 10.

Coupling members 11 and 12, centrally of their confronting side portions, are formed with flat offsets 14, which, when the said members are connected together, space the major part of the said coupling members from each other.

Openings are provided in the flat offsets 14, which communicate with the interior chamber 13, and nipples 15, of double wedge configuration, have their opposite ends 16, disposed in the offset openings of said coupling members 11 and 12 and serve the function of connecting the members 11 and 12 together and for establishing communication between the successive chambers 13.

Likewise openings are provided in the upper and lower walls 17 and 18 respectively of the upper and base coupling members 11 and 12, and said openings are threaded for the reception of the inner tubes 19 which latter extend downwardly through the upper coupling members 11, tubes 10 and the base coupling members 12.

The upper and base couplings 11 and 12 may be connected together at their offset portions 14 by pressure in using nipples 15 or by means of ordinary screw nipples 15' to insure perfect sealing of the same

at these points, and the entire radiator unit is supported upon the floor surface by feet 20 cast integral with the end coupling members.

5 Pipes 21 and 22 are connected by an elbow 23 and lead from the steam or hot water supply, the pipe 22 having a threaded end which takes into a nipple, not illustrated, in the base coupling 12. A valve 24 in pipe 10 21 controls the said supply to the radiator unit and a similar pipe 25 is connected to the top coupling 11 for further circulating the heating element.

It will therefore be seen that the hot 15 water or steam will circulate upwardly through the tubes and downwardly through the upper coupling members 11 to the base member 12. The heating element in this manner has contacting engagement in a 20 tortuous path through the radiator unit with the inner tubes 19, through which the air freely circulates. As the said inner tubes 19 are open at both ends, the air passing therethrough will be heated by the 25 steam or hot water in the tubes 10 and coupling members 11 and 12 and such air by possession of the caloric value, imparted by such heating action, ascends and makes place from the cold air in the lower part 30 of the room.

In such manner, the air at the surface of the room will be heated and thereby a constant supply of heated air will arise from the radiator unit.

35 By this construction, a greater heating area of the radiator is effected, as not only do the inner tubes 19 heat the air but, like-

wise the outer tubes 10 heat the air in the manner of the ordinary type of radiators, and a radiator mountable by unit is provided.

Having thus fully described my invention, what I claim as new and desire to secure by Letters Patent is:—

1. In a radiator the combination of upper and lower coupling members, arranged adjacent each other, nipples connecting said coupling members, vertical tubes passing through the opposite sides of the upper and lower coupling members and surrounding tubes connected to the adjacent sides of said upper and lower coupling members and surrounding the first mentioned tubes placed in relation thereto.

2. In a radiator of the type described the combination of a plurality of upper and lower coupling members, arranged in engagement, and provided with alining openings, nipples extending into said coupling members and engaging the openings therein, and affording a communication between said coupling members and connecting said coupling members together, tubes connecting the adjacent sides of the coupling members and communicating therewith, through openings formed in the adjacent sides of the coupling members and additional tubes passing through these first mentioned tubes and entirely through both sides of said coupling members.

In witness whereof I have hereunto set my hand.

PIERRE JOSEPH HENRI BERNARD.
